UNITED STATES PATENT OFFICE.

EUGENE B. CROCKER, OF PAWTUCKET, RHODE ISLAND.

LEVER-BUTTON.

SPECIFICATION forming part of Letters Patent No. 352,452, dated November 9, 1886.

Application filed July 8, 1886. Serial No. 207,396. (No model.)

To all whom it may concern:

Be it known that I, EUGENE B. CROCKER, of the city of Pawtucket, in the county of Providence and State of Rhode Island, have invented 5 certain new and useful Improvements in Lever-Buttons, of which the following is a full, clear, and exact description, reference being had to the accompanying drawings, forming part of this specification.

10 My invention relates to a lever-button having a movable shoe hinged upon the post, and adapted to swing thereon and assume a position at right angles to said post, to lock the button in a button-hole, or to assume a position somewhat parallel to the post, to facilitate 15 its insertion in or removal from a button-hole.

The objects of my invention are to provide a lever-button of a very simple and inexpensive construction.

20 To the above purposes my invention consists in the peculiar formation of the post of the button out of a wire suitably bent to receive the movable shoe, and, further, of the construction of the movable shoe, all as hereinafter fully described and claimed.

25 In the accompanying drawings, Figure 1 represents a side view of my improved button, with the bent free ends of the wire post shown in broken lines and the shoe thrown down to one side of the post for insertion in or removal from a button-hole. Fig. 2 represents 30 a sectional view on line 2 2, Fig. 1, of the button, with the shoe set at right angles to that shown in Fig. 1. Fig. 3 represents a sectional view of the button taken on line 3 3, Fig. 1.

35 In the said drawings like numbers designate corresponding parts throughout.

Referring to the drawings, the doubled wire or staple 6 is formed at the closed or upper 40 end into a long narrow loop-like opening, and the sides or strands of the wire are bent in toward each other, as at 8, in curved bends, as shown. The open end of the doubled wire 6 is spread out flaringly, and the free ends are 45 secured to the face of the button-head 13 near its circumference.

The doubled wire 6, forming the post of the button and the loop-like bearing at the end for the movable shoe to hinge with, is shown 50 as having said loop and its free ends in the same plane. This, however, may be modified by twisting the post near its center of length,

so that the strands thereof cross or twist on each other X-shaped. The long side 7 of the loop-like formation of the closed end of the 55 doubled wire 6 is constructed semi-cylindrical in cross-section, the upper face thereof being flat, as at 9 in Fig. 2.

The movable shoe is composed of the shoe-cap 12, of a saucer shape, and within the concavity of said cap is firmly set the spring-plate 11, of any suitable shape, though I show it as being a circular plate with two peripheral circular notches arranged in apposition. The hinge-band 10 is a rectangular strip with 60 a transverse curved bend at the center of length. The shoe is secured to the post of the button by first passing the hinge-band 10 through the open area of the closed end of the doubled wire 6, so that the concave face of said band 65 engages the long side 7 of the loop or opening, and then placing the shoe-cap 12, with the spring-plate previously secured therein, upon the hinge-band in the relative positions shown in Fig. 1, and then fastening the free 70 ends of the hinge-band 10 in the circumference of said cap. By virtue of this construction, the spring-plate being made of a suitable 75 resilient metal, the plate is arranged to ride over the flat surface 9 of the side 7 of the bearing and transversely thereto, so that it may be rested at right angles across the same, and thereby securely maintain the shoe in a locked and operative position.

There may be various modifications made in 80 the features of my invention without departing from the spirit of the same, as herein described and claimed. For instance, the sides 85 of the doubled wire 6 may be arranged differently by twisting them or placing them side 90 by side, so as to throw the closed end of the doubled wire out of the plane of the rest of the same, (as shown in an application of mine of even date with this, Serial No. 207,397, for Letters Patent for a necktie-fastener, in which 95 latter application I show various forms of an improved collar-button having the post and the fixed perforated shoe formed of a doubled wire, but for a purpose different from the herein-described one.)

100 I am aware of the construction heretofore of the post of a button from a wire bent square or rectangular, and therefore I disclaim such a constructed button-post, since by my inven-

tion the post is made from a wire doubled or staple in form, and having the closed end thereof formed with a loop as a bearing for the button-shoe, and having the sides or strands 5 thereof bent and placed in contact, or nearly so, and the free ends secured to the button-head; and therefore,

Having thus described my invention, I claim as new and desire to secure by Letters Patent—

10 1. The combination of the button-head, a post secured to said head and formed of a wire bent into a loop or eye at the foot of the post, the sides or strands of the wire intermediate of said loop and the ends bent into contact, or 15 nearly so, and a movable shoe hinged in said eye, substantially as described.

20 2. The combination of the button-head, a doubled wire or staple having the free ends secured to one face of the button-head, the closed end of said wire formed into a long narrow loop having the long axis arranged parallel with the button-head, the sides or strands of the wire bent in toward each other, the 25 closed end of the wire forming the long side of the loop provided with one or more flat faces extending the length of the side, a mov-

able shoe consisting of a cap-plate provided with a spring-band secured thereto, and a hinge-band bent across its length and set transversely of said spring-band, the bend of said hinge-band having its concave face passed through and engaged by said long side of the loop of the wire, the spring-band engaging said long side on an opposite side from said hinge-band, substantially as and for the purpose described.

30 3. The combination of the button-head 7, the doubled wire 6, formed into the post and looped shoe-bearing, and the movable shoe hinged in the bearing of said doubled wire, 35 substantially as described.

4. The combination of the button-head 7, the doubled wire 6, formed into the post and looped shoe-bearing, the movable shoe composed of the shoe-cap 12 and the spring-plate 40 11, and the hinge-band 10, all arranged and constructed substantially as described.

EUGENE B. CROCKER.
